UNITED STATES PATENT OFFICE.

HARRY B. EDGAR, OF COLECAMP, MISSOURI, ASSIGNOR OF TWO-THIRDS
TO HENRY V. ENLOE, OF COLECAMP, MISSOURI.

WAGON-TONGUE SUPPORT.

SPECIFICATION forming part of Letters Patent No. 734,836, dated July 28, 1903.

Application filed November 26, 1902. Serial No. 132,920. (No model.)

To all whom it may concern:

Be it known that I, HARRY B. EDGAR, a citizen of the United States, residing at Colecamp, in the county of Benton and State of Missouri, have invented a new and useful 5 Wagon-Tongue Support, of which the following is a specification.

The invention relates to improvements in wagon-tongue supports.

10 The object of the present invention is to improve the construction of wagon-tongue supports and to provide a simple, inexpensive, and efficient device adapted to be readily applied to a vehicle and capable of yielding 15 supporting the tongue in an elevated position to relieve the draft-animals of strain.

A further object of the invention is to provide a tongue-support of this character which will be capable of ready adjustment to enable 20 the tongue to support additional whiffletrees and which will prevent the tongue, when supported, from bending or breaking its pivot-rod.

25 The invention consists in the construction and novel combination and arrangement of parts hereinafter fully described, illustrated in the accompanying drawings, and pointed out in the claim hereto appended.

In the drawings, Figure 1 is a side elevation, partly in section, of a portion of a vehicle provided with a tongue-support constructed in accordance with this invention. Fig. 2 is a longitudinal sectional view of the same. Fig. 3 is a vertical sectional view on the line 35 3 3 of Fig. 2. Fig. 4 is a detail view of the upper serrated plate. Fig. 5 is a similar view of the lower adjustable serrated plate. Fig. 6 is a detail view of the clip-plate.

Like numerals of reference designate corresponding parts in all the figures of the drawings.

Referring to the drawings, 1 designates a clip-plate or bracket having perforations 2 for the reception of a bolt or other suitable 45 means for securing it to the front axle 3 of a vehicle and having forwardly-extending perforated ears or lugs 4 for the reception of the rear end of a rod or bar 5, and the latter is provided at its rear end with an eye 6, which 50 is pivoted between the perforated ears or lugs 4 by a suitable fastening device 7. The

rod or bar 5 is provided near its rear end with a collar or flange 8, against which abuts the rear end of the coiled spring 9, disposed on the rod and engaging a depending web or 55 flange 10 of a lower adjustable serrated plate or block 11, which engages an upper serrated block or plate 12. The flange 10 depends from the front end of the plate or block and is provided with an opening 13 for the reception of the front portion of the rod or bar 5, which has its front end 14 bent downward to form a stop for preventing the separation of the adjustable block or plate 11 when the parts are assembled and secured to the running-gear, as shown. The flange 10, which is arranged at the front of the block or plate, is supported by tapering side flanges 15, and the latter depend from the block or plate 11, which is also provided with short upwardly-extending flanges 16, forming a recess or groove 70 for the reception of the upper plate 12. The block or plate 11 is provided between the upwardly-extending side flanges with transverse corrugations 17, and it has a longitudinal slot 75 18. The corrugations form approximately triangular ribs or teeth which engage similar ribs or teeth 19, formed by corrugating the lower face of the upper plate 12. The upper plate 12 is secured to the lower face of the 80 tongue by the hammer-strap bolt 20, which passes through a central perforation 21 of the upper corrugated plate and which also extends through the slot of the lower plate or block. The upper plate is provided at its 85 ends with lugs 22, which fit in sockets of the lower face of the tongue to prevent the upper plate from turning on the bolt 20. The bolt 20 is adapted to be loosened to permit the lower block or plate to be moved backward 90 and forward to raise and lower the tongue. By adjusting the lower block or plate backward the tongue is raised, and it may be yielding 95 supported by the same at the desired elevation without liability of bending or breaking the pivot-rod of the tongue through any stiffness of the latter.

It will be seen that the tongue-support is exceedingly simple and inexpensive in construction, that it possesses great strength and 100 durability, and that it is adapted to be readily applied to a vehicle. It will also be seen that

the parts are readily adjustable and that the spring which sustains the weight of the tongue is supported by the rod, which may be readily connected to and disconnected from the lower adjustable block when the parts are detached, but which cannot become separated when the parts are assembled and secured to the running-gear.

Instead of providing lugs for preventing the upper plate from turning on the hammer-strap bolt the plate may be folded to the tongue at opposite sides of the center, and I desire it to be understood that various changes in the form, proportion, size, and minor details of construction within the scope of the appended claim may be resorted to without departing from the spirit or sacrificing any of the advantages of this invention.

What is claimed is—

- The combination of a running-gear, a rod pivoted thereto and having a downwardly and

outwardly curved deflected front end, an upper serrated plate provided with means for interlocking it with the tongue, a lower serrated plate adapted to engage the upper plate and provided with upwardly-extending flanges which embrace the upper plate and constitute a guide, said lower plate having also depending end and side flanges, the end flange having an opening for receiving the front deflected end of the rod, a spring disposed on the rod and engaging the said front flange, and means for securing the lower serrated plate to the upper plate, substantially as described.

In testimony that I claim the foregoing as my own I have hereto affixed my signature in the presence of two witnesses.

HARRY B. EDGAR.
